UNITED STATES PATENT OFFICE

ROBERT H. PLASS, OF MONTCLAIR, NEW JERSEY, ASSIGNOR TO THE CHAPAL DONNER CORPORATION, OF NEWARK, NEW JERSEY, A CORPORATION OF NEW JERSEY

PELT DEHAIRING MACHINE

Application filed December 13, 1929. Serial No. 413,836.

This invention relates to improvements in machines for removing hair or fur from animal skins or pelts; and the invention has reference, more particularly, to novel pelt dehairing mechanism possessing means to so control the movement of the severed hair or fur that waste is reduced to a minimum, and whereby the hair or fur is efficiently separated from skin cuts or slivers.

This invention has for its principal object to provide, in a machine of the kind described, a novel construction and arrangement of rotatable cutting-cylinder or drum cooperative with a stationary cutter-blade, together with novel means for feeding the pelt or skin to such cutting mechanism.

This invention has for a further object to provide adjacent to the cutting point of the machine a novel vibratory rotatable comb device adapted to engage the severed hair or fur and quickly deliver the same outward and away from the cutting mechanism in condition free from skin cuts or slivers.

Other objects of this invention, not at this time more particularly enumerated, will be understood from the following detailed description of the same.

An illustrative embodiment of this invention is shown in the accompanying drawings, in which:

Fig. 1 is a side elevation of the novel dehairing machine, with parts broken away and other parts in section; Fig. 2 is a top or plan view of the machine; Fig. 3 is an enlarged fragmentary vertical section taken on line 3—3 in Fig. 2, showing the drive for the vibratory rotatable comb device, and the feed roller control means; Fig. 4 is an enlarged fragmentary vertical section, taken on line 4—4 in Fig. 2; Fig. 5 is a further enlarged sectional view illustrating the function of the comb device; and Fig. 6 is a perspective of parts of one form of comb roll.

Similar characters of reference are employed in all the above-described views, to indicate corresponding parts.

Referring now to said drawings, the reference character 10 indicates a cutting cylin-

der or drum, the shaft 10 of which is journaled in bearings 11 supported on the frame-work 12 of the machine. Suitably secured to the cutting cylinder or drum are a plurality of radial and preferably longitudinal 55 oblique shear blades 13. Secured to the machine frame, so as to extend over and enclose the upper forward side of the cutting cylinder or drum 11, is a bed-knife frame 14 to which is suitably and adjustably secured a stationary or bed-knife 15. Said bed-knife 15 is mounted with its cutting edge downward, and is disposed substantially parallel to the axis of said cutting cylinder or drum 11, so that the shear 60 blades 13, which are revolved by the latter, may cooperate with the cutting edge of said bed knife.

Mounted on the frame-work 12, forwardly of the cutter mechanism, are fixed side plates 70 16. Journaled in and extending between said side plates 16 is a shaft 17. Pivoted on said shaft 17 are lever members 18, which respectively lie adjacent to the inner faces of the side plates 16. A feed roller 19 extends between the inner ends of said lever members 18, the journals 20 of said roller being rotatably engaged through bearing openings provided in said lever members 18. As thus supported, said feed roller is located in front 75 80 of and closely adjacent to the cutting point of the cutting mechanism.

Pivotedly mounted on said shaft 17, to lie side by side throughout the space between said lever members 18, are a plurality of pelt 85 supporting members 21, which together provide a feed table over which pelts may be fed to the cutting point of the machine. Each supporting member 21 terminates at its inner end in a curved guide portion 22 which is opposed to and which substantially conforms to the under surface contour of feed roller 19. Each supporting member 21 is normally positioned, with its guide portion 90 95 22 slightly spaced from the surface of said feed roller 19, by engagement of a tail-piece 23 thereof with a stop-ledge 24 secured to and between the side plates 16. Said supporting members are yieldably biased to such normal positions by pull-springs 25, adapted 100

to exert downwardly swinging tension on the outer or tail ends thereof. Said supporting members 21 serve to guide a pelt, fed toward the cutting point of the machine, 5 to, under and into propelled engagement by said feed roller 19. Since, however, each supporting member 21 is individually yieldable, some one or more of the same will yield to the passage of burrs, excrescences or 10 the like occurring in the pelt at any given point, without disturbing the function of the remaining supporting members in pressing the pelt into propelled engagement with said feed roller 19, and consequently such imperfections in the pelt will not interfere with or obstruct in any way the desired steady, uniform and smooth movement of the pelt to the cutting point of the machine.

Secured to the front face of the stationary or bed knife 15, to extend intermediate the lower margin of the same and the normally positioned feed roller 19, is a feller or doctor piece 26, which serves to lead the pelt, as fed forward by said feed roller 19, from 25 the latter to and over the cutting edge of said stationary or bed knife 15.

Means are provided, under control of the operator of the machine, for selectively disposing the feed roller in service or out-of-service position, i. e. in pelt feeding or pelt releasing position. This means comprises a fulcrum shaft 27, journaled in and extending between said side plates 16, with the respective ends projecting exteriorly beyond the outer faces of said side plates. Fixed on the respective exterior ends of said fulcrum shaft 27 are lever members 28. Secured to and extending between the outer ends of said lever members 18 is a transverse connecting shaft 29, having extensions 30, preferably of reduced diameter, which extend through slots 31 provided in the side plates 16 so as to engage in slotted openings 32 with which the inner ends of said lever members 28 are provided, thus operatively interconnecting said lever members 28 with lever members 18. Pivottally mounted on fulcrums 33 in front of the machine is leverage platform 34, the forward end of 50 which is interconnected with the outer ends of said lever members 28 by links 35. Forward stop blocks 36 and rearward stop blocks 37 operate to limit the oscillatory movements of said leverage platform 34.

55 In the use of the machine, the operator stands on the leverage platform 34, and when desirous of introducing a pelt beneath the feed roller 19, preparatory to feeding such pelt to the cutting point of the machine, steps back on the leverage platform 34 so as to apply weight to the outer end thereof, whereby the inner end of leverage platform 34 is up-swung. This movement of the leverage platform is transmitted to the 60 outer ends of lever members 28, which outer

ends are thereby upwardly moved with consequent downward movement of the inner ends thereof. Through the coupling connections between lever members 28 and 18, the downward movement of the inner ends 70 of the former produces an accompanying downward movement of the outer ends of the latter, whereby the inner ends thereof are up-swung, thus raising the feed roller 19 away from the yieldable supporting members 21 so that the leading end of the pelt may be introduced between such parts. When the pelt is thus introduced, the operator steps forward on the leverage platform 80 so as to apply weight to the inner end thereof, with consequent reversal of the above-described lever movements, whereby the feed roller is lowered into the pelt gripping relation to supporting members 21 and thereupon progressively fed forward, fur side 85 down, to the cutting mechanism. Stop screws 38 are adjustably mounted in the side plates 16 to enter the slots 31, so as to engage the extensions 30, thus limiting the movement of the gripping roller 19 to desired pelt gripping relation to the supporting members 21.

Any suitable form and arrangement of power transmission means may be provided for applying operating power to the cutting 95 cylinder or drum 10 and to the feed roller 19. Illustrative of one form and arrangement of power transmission means, the shaft 10' of the cutting cylinder or drum 10 is shown provided with a drive pulley 39, over 100 which runs a drive belt 40 actuated from any desired source of power. Journaled in bearings 41, connected with the frame-work 12 of the machine, is a counter shaft 42, actuated from said shaft 10' by a belt and pulley drive 43 or equivalent interconnecting transmission. Fixed on one of the side plates 16, to project exteriorly therefrom, is a stub shaft or journal 44, on which is rotatably mounted a hollow shaft or sleeve 45. 110 Fixed on the outer end of said hollow shaft or sleeve 45 is a pulley wheel 46, over which runs a drive belt 47, driven by a pulley wheel 48 fixed on and rotated by said counter shaft 42. Fixed on the inner end of said hollow shaft or sleeve 45 is a spur gear 49. Mounted on a projecting end of the pivot shaft 17 of said lever members 18, is a hollow shaft or sleeve 50, on the outer portion of which is fixed a gear wheel 51, which meshes with and is driven by said spur gear 49. Fixed on the inner portion of said hollow shaft or sleeve 50 is a gear 52, which gear 52 meshes with and drives an idler gear 53 journaled on a stub-shaft 54 carried by 120 the adjacent lever member 18. Fixed on the shaft or journal of said feed roller 19 is a gear 55 which meshes with and is driven by said idler gear 53. It will thus be obvious that operating power may be constant- 130

ly applied to said feed roller 19, without interfering with the free movement thereof into service or out-of-service positions relative to said supporting members 21 as may be desired.

In practice, the cutting cylinder or drum 10 is enclosed. The enclosure is effected in part by the bed-knife frame 14 and in part by a hood member 56, and below the cutting point by any suitable partition means 57, adapted to leave space giving access to the cutting point for pelts delivered thereto by the feeding mechanism. The cutting cylinder or drum 10 is thus arranged to revolve in a chamber 58 which is open at its rearward underside to communicate with a drop-well or discharge passage 59. Leading laterally from the drop-well or discharge passage 59, beneath the chamber 58 is a fur conveyer 20 passage 60 and conduit 60'.

In the operation of the machine, the rotation of the cutting cylinder or drum, at its forward face and relative to the cutting point thereof, is upward. The revolution of the cutting blades 13 produces a centrifugal air current within the chamber 58 in the direction of motion of the cutting cylinder or drum. As slivers of hide or skin are cut from the pelt, while severing the hair or fur from the latter, the same are carried around the chamber 58 by the centrifugal air current, and discharged into the drop-well or passage 59, and being relatively heavy will gravitate through the latter.

One of the most important features of this invention relates to the provision of a novel construction and arrangement of means for rapidly and efficiently removing the hair or fur severed from the pelts by the cutting operation, and delivering the same from the cutting point of the machine substantially free from slivers of skin or hide, and with minimum of waste or loss of severed hair or fur. This means comprises a comb device 40 located adjacent to the cutting point of the machine, and adapted to quickly and efficiently outwardly withdraw the severed hair or fur from the cutting point of the machine. The comb device is preferably made 45 in the form of a roller 61 having rows of radial teeth 61' projecting therefrom, the same being mounted adjacent to and beneath the bed-knife 15 and as close to the path of movement of the cutting blades 13 as possible, while nevertheless clearing the latter. Preferably said comb roller 60 is mounted 50 for oscillatory or vibratory bodily movement toward and from the fur side of a pelt undergoing the cutting operation. To this 55 end carrying arms 61 are pivotally connected on the shaft 17 to extend forward at each side of the machine toward the cutting point. The comb roller 60 is journaled in and extends between the free ends of said 60 carrying arms 62. Journaled in and be-

tween the side plates 16 below the cutting point of the machine, is a crank shaft 63 having eccentric crank portions 64. Mounted on said crank portions 64 are eccentric arms 65, the upper free ends of which are 70 pivotally connected with ears 62' of the carrier arm 62.

Said crank-shaft 63 is driven by suitable power transmission means, as, for example, by a pulley 66 over which runs a crossed belt 67 driven from a pulley 68 fixed on said counter-shaft 42. Said comb roller 60 is driven from said crank-shaft 63 by a sprocket and chain drive 69, so that the same is rotated in the direction of the arrow 80 shown in Fig. 5.

In operation, as the pelt is fed from beneath the feed roller 19 and advanced across the edge of the belt-knife 15, the fur or hair will be laid back along the underside of the pelt, exposing the bases of the filaments thereof to the cutting action of the blades 13 of the cutting cylinder or drum 10. As a blade 13 passes the bed-knife 15 a sliver of hide or skin will be cut away from the pelt, at the same time severing the hair or fur filaments from such sliver. The sliver will be carried around in the centrifugal air current within the chamber 58 and finally cast down into the drop well or passage 59. 95 The severed hair or fur filaments will be combed back by the rotating comb roller 62, and will be thus separated from the filaments still attached to the pelt by the combing action, being at the same time thrust outwardly to fall on a collecting chute 70, down which the same may slide to any suitable receptacle (not shown) placed for the reception thereof. The vibratory or oscillatory movement of the comb roller, not only prevents any tendency of mass choking of hair or fur filaments between the pelt and comb roller, but also tends to permit a tangled interlacing of the severed hair or fur filaments so as to form a more or less loose batting of the discharged hair or fur mass.

Owing to the fact that the movement of the cutting blades 13 of the cylinder or drum 10 is upwards toward the cutting point established by the bed-knife 15, with accompanying air current movement in the same direction, there is a tendency of air to pass outward beneath the bed-knife 15 and toward the comb roll 62. This outwardly moving air aids in directing the severed hair or fur filaments outwardly from the machine and into engagement with the comb roller. A vertically adjustable plate 71, may be fixed across the opening established at the cutting point of the machine, to more or less govern the volume of air out-passing at such point.

It is preferable to provide an up-passing light air current within the drop well or

passage 59, whereby any severed hair or fur particles, which are carried around by the air current in chamber 58 and discharged in the upper end of the drop-well or passage 59, will thereupon meet the rising air current so as to be floated out through the conduit 61, and thus recovered so as to further reduce waste or loss of hair or fur filaments. The rising air current in the drop-well or passage 59 is maintained mild enough in character to avoid interfering with gravitation of the hide or skin slivers through the drop-well or passage 59, and consequently a separation and recovery of stray hair and fur filaments from slivers is thereby attained.

From the above description, it will be apparent that this invention provides a simple and yet efficient dehauling machine, calculated to operate with minimum loss of severed hair or fur filaments.

I am aware that many changes could be made in the above described mechanisms making up the novel dehauling machine as well as in the details of the construction thereof, without departing from the scope of this invention, and therefore it is intended that all matter contained in the above description or shown in the accompanying drawings shall be interpreted as illustrative and not in a limiting sense.

I claim:—

1. In a machine of the kind described, a cutting mechanism, means to feed pelts to said cutting mechanism, and a movable comb means adjacent the cutting mechanism operative to sweep outwardly and away from the cutting mechanism and a pelt fed thereto hair or fur filaments severed from the latter.

2. In a machine of the kind described, a cutting mechanism, means to feed pelts to said cutting mechanism, and a rotatable comb-roller having radial teeth projecting from its surface, said comb-roller being disposed adjacent to the cutting mechanism and operative to sweep outwardly and away therefrom and from a pelt hair or fur filaments severed from the latter.

3. In a machine of the kind described, a cutting mechanism, means to feed pelts to said cutting mechanism, a rotatable comb-roller having radial teeth projecting from its surface, said comb-roller being disposed adjacent to the cutting mechanism and operative to sweep outwardly and away therefrom and from a pelt hair or fur filaments severed from the latter, and means for producing oscillatory bodily movement of said comb-roller toward and away from said pelt.

4. In a machine of the kind described, a cutting mechanism, a rotatable feed roller in front of said cutting mechanism, means to drive said feed roller, and a series of

independently yieldable pelt guiding and supporting fingers having their forward ends underlying and biased toward said feed roller, said fingers being arranged side by side to provide a pelt supporting surface substantially coextensive with the extent of said feed roller, and means to positively limit the movement of said fingers toward said feed roller.

5. In a machine of the kind described, a cutting mechanism, a rotatable feed roller in front of said cutting mechanism, means to drive said feed roller, and a series of independently yieldable pelt guiding and supporting fingers having their forward ends underlying and biased toward said feed roller, said fingers being arranged side by side to provide a pelt supporting surface substantially coextensive with the extent of said feed roller, means to positively limit the movement of said fingers toward said feed roller and means to selectively move said feed roller to "in-service" or "out-of-service" relation to said fingers.

6. In a machine of the kind described, a cutting mechanism, a rotatable feed roller in front of said cutting mechanism, means to drive said feed roller, and a series of independently yieldable pelt guiding and supporting fingers having their forward ends underlying and biased toward said feed roller, said fingers being arranged side by side to provide a pelt supporting surface substantially coextensive with the extent of said feed roller, means to positively limit the movement of said fingers toward said feed roller and means to selectively move said feed roller to "in-service" or "out-of-service" relation to said fingers, said means comprising a leverage system by which said feed roller is supported, the same being subject to actuation by applied weight of the operator positioned in front of the machine.

7. In a machine of the kind described, a cutting mechanism, a rotatable feed roller in front of said cutting mechanism, means to drive said feed roller, a series of independently yieldable pelt guiding and supporting fingers opposed to said feed roller, and a movable comb means intermediate said cutting mechanism and said fingers and opposed to a pelt fed to said cutting mechanism so as to sweep outwardly and away from said cutting mechanism and pelt hair or fur filaments severed from the latter.

8. In a machine of the kind described, a cutting mechanism, a rotatable feed roller in front of said cutting mechanism, means to drive said feed roller, a series of independently yieldable pelt guiding and supporting fingers opposed to said feed roller, a movable comb means intermediate said cutting mechanism and said fingers and opposed to a pelt fed to said cutting mechanism so as to sweep outwardly and away from

- 5 said cutting mechanism and pelt hair or fur filaments severed from the latter, and a leverage system by which said feed roller is supported, said leverage system being subject to actuation by applied weight of the operator positioned in front of the machine to selectively move said feed roller to "in-service" or "out-of-service" relation to said fingers.
- 10 9. In a machine of the kind described, a cutting mechanism, a rotatable feed roller in front of said cutting mechanism, means to drive said feed roller, a series of independently yieldable pelt guiding and supporting fingers opposed to said feed roller, a rotatable comb-roller having radial teeth projecting from its surface, and means for producing oscillatory bodily movement of said comb-roller toward and away from said pelt.
- 15 10. In a machine of the kind described, a cutting mechanism, a rotatable feed roller in front of said cutting mechanism, means to drive said feed roller, a series of independently yieldable pelt guiding and supporting fingers opposed to said feed roller, a rotatable comb-roller having radial teeth projecting from its surface, means for producing oscillatory bodily movement of said comb-roller toward and away from said pelt, and a leverage system by which said feed roller is supported, said leverage system being subject to actuation by applied weight of the operator positioned in front of the machine to selectively move said feed roller to "in-service" or "out-of-service" relation to said fingers.
- 20 11. In a machine of the kind described, a rotatable cutting cylinder having radial shear-blades, a stationary knife having a cutting edge at its lower margin, said cutting cylinder being rotatable in a direction adapted to carry its shear blades upwardly relative to and in contact with said stationary knife cutting edge, and a movable comb means adjacently below said stationary knife cutting edge operative to sweep outwardly and away therefrom and from a pelt fed thereto hair or fur filaments severed from the latter.
- 25 12. In a machine of the kind described, a rotatable cutting cylinder having radial shear-blades, a stationary knife having a cutting edge at its lower margin, said cutting cylinder being rotatable in a direction adapted to carry its shear blades upwardly relative to and in contact with said stationary knife cutting edge, means to feed pelts beneath the stationary knife cutting edge, and a movable comb means adjacently below said stationary knife cutting edge operative to sweep outwardly and away therefrom and from a pelt fed thereto hair or fur filaments severed from the latter, said
- 30 latter means comprising a rotatable comb roller having a multiplicity of radial teeth, means to drive said comb roller, and means for producing oscillatory bodily movement of said comb roller toward and away from said pelt.
- 35 13. In a machine of the kind described, a rotatable cutting cylinder having radial shear-blades, a stationary knife having a cutting edge at its lower margin, said cutting cylinder being rotatable in a direction adapted to carry its shear blades upwardly relative to and in contact with said stationary knife cutting edge, a rotatable feed roller in front of said stationary knife cutting edge, means to drive said feed roller, a series of independently yieldable pelt guiding and supporting fingers underlying said feed roller, a rotatable comb roller having a multiplicity of radial teeth mounted adjacently below said stationary knife cutting edge, means to drive said comb roller, and means for producing oscillatory bodily movement of said comb roller toward and away from a pelt moved by said feed roller to said stationary knife cutting edge.
- 40 14. In a machine of the kind described as defined in claim 13, including a leverage system by which said feed roller is supported, said leverage system being subject to actuation by applied weight of the operator positioned in front of the machine to selectively move said feed roller to "in-service" or "out-of-service" relation to said yieldable pelt guiding and supporting fingers of the machine.
- 45 15. In a machine of the kind described, a cutting mechanism including a rotatable cutting cylinder and a stationary knife cooperative therewith, means to feed pelts to said cutting mechanism, a movable comb means adjacent to said cutting mechanism operative to sweep outwardly and away from the cutting mechanism and a pelt fed thereto hair or fur filaments severed from the latter, means to enclose said cutting cylinder beyond the cutting point thereof to form an air circulation chamber through which pelt slivers are moved by air currents induced by movement of said cutting cylinder, and a drop well communicating with said chamber to receive pelt slivers discharged therefrom.
- 50 16. In a machine of the kind described, a cutting mechanism including a rotatable cutting cylinder and a stationary knife cooperative therewith, means to feed pelts to said cutting mechanism, a movable comb means adjacent to said cutting mechanism operative to sweep outwardly and away from the cutting mechanism and a pelt fed thereto hair or fur filaments severed from the latter, means to enclose said cutting cylinder beyond the cutting point thereof to form an air circulation chamber through

which pelt slivers are moved by air currents induced by movement of said cutting cylinder, a drop-well communicating with said chamber to receive pelt slivers discharged therefrom, and a branching conduit leading from upper portion of said drop-well to discharge a comparatively light air current directed upwardly through said drop-well to thereby separate and carry away any hair or fur filaments accompanying said pelt slivers into said drop-well.

In testimony, that I claim the invention set forth above I have hereunto set my hand this 10th day of December, 1929.
